GEORGE B. AMBLER, OF BRIDGEPORT, CONNECTICUT.

Letters Patent No. 91,062, dated June 8, 1869.

IMPROVEMENT IN VELOCIPED-SADDLES.

The Schedule referred to in these Letters Patent and making part of the same.

To all whom it may concern:

Be it known that I, GEORGE B. AMBLER, of Bridgeport, in the county of Fairfield, and State of Connecticut, have invented a new Improvement in Velocipede-Saddle; and I do hereby declare the following, when taken in connection with the accompanying drawings, and the letters of reference marked thereon, to be a full, clear, and exact description of the same, and which said drawings constitute part of this specification, and represent, in—

Figure 1, a top view;

Figure 2, a side view; and in

Figure 3, a rear-end view.

This invention relates to an improvement in the saddle, or seat of velocipedes. These have heretofore been formed from metal, a material which is difficult to cover to form a stuffed seat, and one which adds greatly to the weight of the carriage.

My invention consists in a velocipede-seat, as an article of manufacture, constructed and shaped from wood, and strengthened and provided with means of attachment to the velocipede.

In order to the clear understanding of my invention, I will fully describe the same, as illustrated in the accompanying drawings.

From wood, (preferring several pieces, the grain of one piece crossing the grain of the other,) I form the seat A, with the horn B projecting forward, shaped into a comfortable form for the rider, and this I cover

with a fabricated material, as canvas, glued, sized, or otherwise caused to adhere closely to the wood.

Across the seat, upon the under side, I place a bar of metal, *a*, as a means of strengthening the seat, and to the seat I attach bolts *d*, passing through the seat, and headed upon a cross-bar upon the upper side, the said bolts serving, with the bar *h*, as a means of attachment to the velocipede.

This forms, as a whole, an article of manufacture, the consumer applying and upholstering the seat according to his taste.

The advantages of this seat over the common iron seat are its lightness and ease, inasmuch as it may be made much larger and lighter than the iron seat, and, from the nature of the material, is more easily upholstered than an iron seat.

I do not wish to be understood as broadly claiming a wood saddle-tree, covered with a fibrous material, as such is not new.

Having fully described my invention,

What I claim as new and useful, and desire to secure by Letters Patent, is—

As a new article of manufacture, a velocipede-seat, or saddle-tree, substantially as herein described, consisting of the seat A and means of attachment, all as shown and specified.
